Maier & Neustadt, P.C.

(**) Term: **14 Years**

(57) **CLAIM**

The ornamental design for a massaging apparatus, as shown and described.

DESCRIPTION

Jun. 13, 2001 (JP) 2001-017276

(51) LOC (7) Cl. **28-03**

FIG. 1 is a bottom and left front perspective view of a massaging apparatus, showing our design;

(52) U.S. Cl. **D24/212**

FIG. 2 is a front elevational view thereof;

(58) Field of Search D24/200, 212,
D24/215; 601/23, 33, 34, 35, 46, 49, 50,
56, 57, 84—86, 97, 98, 93, 101

FIG. 3 is a right side elevational view thereof, the left side elevational view being a mirror image of the side view shown;

(56) **References Cited**

FIG. 4 is a top plan view thereof;

U.S. PATENT DOCUMENTS

FIG. 5 is a rear elevational view thereof;

3,035,557 A * 5/1962 Nelson 601/31
5,107,822 A * 4/1992 Ohashi 601/23
